COUPLER AND YOKE CONNECTION

Edward H. Lehman, Chicago, Ill., assignor to
W. H. Miner, Inc., Chicago, Ill., a corporation
of Delaware

Application October 29, 1931. Serial No. 571,830

3 Claims. (Cl. 213—70)

This invention relates to improvements in coupler and yoke connections.

One object of the invention is to provide simple and efficient means for connecting the coupler and yoke of a railway draft rigging, wherein ready attachment of the coupler is had by means of a single locking element having shouldered engagement with the yoke to prevent accidental removal thereof and held in place and in said 10 shouldered engagement by the coupler butt.

A more specific object of the invention is to provide means of the character described in the preceding paragraph, wherein the yoke is provided with a seat in which a locking block is 15 disposed having shouldered engagement with the yoke to hold the block against longitudinal displacement with respect to the yoke, having shouldered engagement with the coupler butt to limit outward movement of the coupler with respect to the yoke, and having locking engagement with the yoke by means of tongue and groove formations thereon to prevent accidental lateral displacement of the block with respect to the yoke.

25 Other objects of the invention will more clearly appear from the description and claims hereinafter following.

In the drawing, forming a part of this specification, Figure 1 is a side elevational view of 30 a yoke member and a portion of the cooperating coupler, illustrating my improvements in connection therewith. Figure 2 is a horizontal sectional view, corresponding substantially to the line 2—2 of Figure 1. Figure 3 is a transverse, 35 vertical sectional view, corresponding substantially to the line 3—3 of Figure 1. Figure 4 is a view similar to Figure 1, partly broken away, illustrating another embodiment of the invention. And Figure 5 is a transverse, vertical sectional view, corresponding substantially to the 40 line 5—5 of Figure 4.

45 Referring first to the embodiment of the invention illustrated in Figures 1, 2, and 3, the coupler is indicated by 10, the shank and butt portion thereof only being shown. The butt of the coupler, which is indicated by 11, has top and bottom transverse shoulders 12—12. The coupler 10 is connected to a yoke 13, which is 50 of the vertical type, having top and bottom arms 14—14, a vertical rear end section 16, and connecting spaced side webs 17—17 at the forward end.

55 In carrying out my invention as illustrated in Figures 1, 2, and 3, the lower arm 14 of the yoke is downwardly offset at the forward end, as in-

dicated at 18. Immediately to the rear of the connecting webs 17—17, the offset section 18 of the arm 14 is provided with a transverse recess 19 forming a seat for a locking block A. Between the webs 17—17, the upper surface of the bottom arm 14 is in horizontal alignment with the bottom wall of the seat 19. The seat 19 defined by the recess has transverse front wall sections 20—20 and transverse rear wall sections 21—21. Rearwardly of the seat 19, the bottom arm 14 of the yoke is inclined upwardly, as indicated at 22, said upwardly inclined portion being centrally recessed at the upper side, as indicated at 23.

70 My improved locking block A, which is employed to connect the shouldered coupler butt to the yoke, is in the form of a relatively heavy plate having an upstanding transverse front wall or rib 24 and relatively short spaced side walls or ribs 25—25 extending rearwardly from said front wall. The ribs or walls 25—25 are spaced apart such a distance as to accommodate the coupler butt member therebetween, and the front wall is of such a height as to have shouldered engagement with the lower shoulder 12 of the coupler butt. At the rear end, the plate member A is provided with a rearwardly projecting tongue 26, which extends into the recess 23, thereby locking the block A against lateral displacement with respect to the yoke. The coupler butt rests on the block A between the walls 25—25 thereof and has the upper shoulder 12 thereof in shouldered engagement with a transverse abutment shoulder 27 provided on the top arm 14 of the yoke in vertical alignment with the inner face of the transverse wall 24 of the block A.

75 In assembling the parts, the coupler shank is entered between the top and bottom yoke arms through the front end of the yoke and moved rearwardly to the dotted line position indicated by 28 in Figure 1. The shoulders 12—12 of the butt are thus disposed rearwardly of the seat 19 of the lower arm 14 so that the block A, together with its rearwardly projecting tongue 26, will clear the lower shoulder of the butt of the coupler shank when the block is inserted laterally into the yoke. The block A is placed within the yoke above the seat 19 and dropped into the same with the tongue 26 engaging within the seat 23. The coupler is then pulled forwardly so that the coupler butt rests on the block A, and the draft gear is then placed within the yoke. The draft gear will thus yieldingly maintain the coupler butt in its outermost position and in overlapping relation with the retaining block A. As 80 85 90 95 100 105 110

will be evident, the coupler is movable inwardly with respect to the yoke to compress the shock absorbing mechanism, but is limited in its outward movement by engagement with the end wall 24 of the block A. Inasmuch as the block is in shoudered engagement with the yoke, outward movement of the block is prevented, and when movement of the coupler is limited by shoudered engagement with the block, the yoke will be pulled outwardly with the coupler. As will be evident, the coupler butt resting on the block A prevents lateral displacement of the tongue 26 from the recess or seat 23.

Referring next to the embodiment of the invention illustrated in Figures 4 and 5, the yoke is broadly of the same design as the yoke illustrated in Figure 1, and has top and bottom arms 114-114 connected by vertically disposed spaced side webs 117-117 at the outer end of the yoke. The bottom arm of the yoke is downwardly offset in a manner similar to the arm 14 of the yoke shown in Figure 1, said offset portion being designated by 118. The offset portion 118 is recessed rearwardly of the webs 117-117, thereby providing a transverse seat 119. The seat 119 has front and rear limiting walls 120 and 121. The bottom wall of the seat 119 is provided with a longitudinally extending central groove 122, which cooperates with the locking block B in a manner hereinafter described.

The locking block B has a transverse front wall 123 at the upper side thereof, which has shoudered engagement with the bottom shoulder 112 of the coupler butt 111. The upper arm 114 of the yoke is provided with an abutment shoulder 127 in alignment with the inner face of the wall 123, which shoulder has engagement with the upper shoulder 112 of the coupler butt. The retaining block B is provided with a bottom rib 130, which engages within the groove 122 and thereby holds the block B against accidental lateral displacement with respect to the yoke.

The yoke and coupler shown in Figures 4 and 5 are assembled in a manner similar to that hereinbefore described in connection with Figures 1, 2, and 3, the block B being inserted within the yoke while the coupler butt is disposed rearwardly of the recess or seat 119. The block is dropped into the seat and the tongue 130 thereof engaged within the groove 122. When the draft gear has been assembled with the yoke, the coupler will be yieldingly held in the position shown in Figure 4, with the butt member thereof resting on the locking block B, thereby holding the tongue 130 thereof engaged within the groove 122.

I have herein shown and described what I now consider the preferred manner of carrying out my invention, but the same is merely illustrative and I contemplate all changes and modifications that come within the scope of the claims appended hereto.

I claim:

1. In a coupler and yoke connection, the combination with a coupler having a shoudered butt;

of a vertical yoke having top and bottom arms between which the coupler butt is disposed, said yoke also having side webs connecting the outer ends of said arms, said side webs embracing the coupler shank and butt, the bottom arm of said yoke having a seat rearwardly of said webs for receiving a locking block and holding the same against movement lengthwise of the yoke, said bottom arm of the yoke having upstanding, laterally spaced guide ribs rearwardly of said seat, said ribs having flat top guide surfaces for supporting the coupler butt; and a locking block disposed within said seat, said locking block having a transverse wall having shoudered engagement with the shoudered butt of the coupler to limit outward movement of the coupler with respect to the yoke, said block having a rearwardly extending tongue engaging between the ribs of said bottom arm of the yoke to hold said block against accidental lateral displacement with respect to the yoke, the upper surface of said tongue being flush with the flat guide surfaces of said ribs.

2. In a coupler and yoke connection, the combination with a coupler having a shoudered butt; of a yoke adapted to receive the butt end of a coupler shank; and a locking block having shoudered engagement with the yoke and coupler butt to limit outward movement of the coupler with respect to the yoke, said block and yoke having interengaging means thereon of tongue and groove formation for preventing accidental lateral displacement of the block with respect to the yoke, said groove being defined by spaced longitudinal ribs, said ribs and tongue having top guide surfaces supporting the coupler butt.

3. In a coupler and yoke connection, the combination with a coupler having a shoudered butt; of a vertical yoke having top and bottom arms between which the coupler butt is disposed, said yoke also having spaced side webs connecting the outer ends of said arms and embracing the coupler shank, said bottom yoke arm having a transverse opening rearwardly of said webs providing a seat for a locking block; and a locking block in said seat having shoudered engagement with the front wall of the seat to hold said block against forward movement with respect to the yoke, said block having a longitudinally extending, flat upper supporting surface for said coupler butt, a transverse top wall at the forward end in shoudered engagement with the coupler butt to limit outward movement of the coupler shank with respect to the yoke, and a rearwardly extending central tongue having a flat top surface forming a continuation of said supporting surface, said lower yoke arm having a pocket rearwardly of the seat defined by spaced side walls between which said tongue engages to hold the block against lateral displacement with respect to the yoke, said side walls having top surfaces flush with the supporting surfaces of said block and tongue.

EDWARD H. LEHMAN.
